B. L. Marble Furniture Inc., Bedford, Ohio, a corporation of Ohio

Filed Oct. 1, 1965, Ser. No. 87,256

Term of patent 14 years

(Cl. D33—7)

The dominant features of my design reside in the portion shown in full lines on the drawing, and is comprised of a continuous arcuate front edge and continuous arcuate side edges, the center of curvature of said side edges being positioned rearwardly of the lateral center line of said top, said front edge and said arcuate side edges terminating in sharply defined corners, all as shown.

I claim:

The ornamental design for a desk, substantially as shown and described.
